EDWIN H. PIERSEN, OF TOPEKA, KANSAS.

CIRCUIT MAKING AND BREAKING DEVICE.

1,416,973.

Specification of Letters Patent. Patented May 23, 1922.

Application filed October 2, 1919. Serial No. 328,051.

To all whom it may concern:

Be it known that I, EDWIN H. PIERSEN, a citizen of the United States, residing at Topeka, in the county of Shawnee and State 5 of Kansas, have invented certain new and useful Improvements in Circuit Making and Breaking Devices; and I do declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

My invention relates to circuit making and breaking devices and more particularly to a contact device for use in connection with telegraph transmitters of the type shown 20 and described in my co-pending reissue application, Serial No. 313,705, filed May 17, 1919, wherein the circuit making and breaking device is selectively operated by suitable means illustrated as a perforated tape to 25 cause the line to transmit impulses corresponding to dots and dashes of telegraphic characters.

In order that a device of this class may 30 simulate hand sending and insure standard spacing between impulses and characters, the spacing between perforations in the tape and between sets of character perforations must be standardized to avoid confusion at the receiving end. While such standardization 35 is sufficient for ordinary conditions, it is well known that a certain flexibility is essential on account of varying conditions of weather or distance affecting transmission of the current through the line. For example, in transmission over short lines and under favorable conditions where substantially 40 a uniform voltage is maintained over the entire line, the space interval is sharply defined and may consequently be short; whereas, in transmission over long lines where there is a drop in voltage or under adverse weather conditions, or where there is a line leak due to moisture or the like, confusion of the impulses and "piling up" at 45 the receiving station is liable to result unless the sending contacts are separated by intervals greater than those employed under favorable conditions.

It is, therefore, the object of the present 55 invention to provide a circuit making and

breaking device which, while simple in construction and operation, is adaptable for adjustments to effect variations in spacing to meet the conditions above mentioned.

In accomplishing this object, I have provided improved details of structure, the preferred forms of which are illustrated in the accompanying drawings, wherein,

Fig. I is a perspective view of a circuit making and breaking mechanism embodying 65 my invention and illustrating its application to a telegraph transmitter of the perforated tape type.

Fig. II is a transverse vertical section of a portion of a transmitter of this type on the 70 line of the finger axis.

Fig. III is a longitudinal vertical section on the line III—III of Fig. II, showing the points set at an intermediate position.

Fig. IV is a similar view showing the 75 points set for a long contact and short space.

Fig. V is a similar view showing the points set for a short contact and long space.

Fig. VI is a detail sectional view of the 80 stationary contact and its mounting.

Referring more in detail to the drawings:

1—1' designate side members of the frame of a transmitter and 2 a roller which is journaled in the side members and adapted to support a perforated tape 3, the said roller 85 having circumferential grooves 4 over which the perforated portions of the tape may travel for the purpose presently set forth. Also journaled in the frame sides 1—1' parallel with the roller 2 is a shaft 5. Fixed on the ends 90 of the shaft 5 are standards 6—6', the former having a shoulder 7 formed by cutting away the upper portion thereof to seat a universal bar 8 which is attached to the shoulder by a screw 9 and to the top of the 95 opposite standard 6' by a screw 10. The extension 11 of the standard 6 carries a forwardly directed contact point 12 adapted for engaging a mating point 13 adjustably mounted on the head 14 of the bracket 15 100 that is fixed to the frame side 1 by screws 16. The bracket is insulated from the frame side by a suitable non-conductor 17 and the point 13 is insulated from the bracket by a non-conductor 18 to avoid short circuiting 105 when the contact points meet.

The bracket 15 has an extension arm 19 provided with a binding post 20 to which a line wire 21 is attached. The other line wire 22 is connected with a binding post 23 that 110

is grounded on the frame side 1 to close the circuit when the contact points meet.

One of the contact points, here shown to be the one on bracket 15, is preferably made 5 adjustable, by screw-threading the shank 24 carrying the point and mounting the shank in the collar 14, the end of the shank opposite the contact point carrying a knurled button 25 and a jam-nut 26 whereby the 10 shank may be positioned and anchored to its carrying collar. The contact points are normally yieldingly separated by means of a spring 27 which is attached to the standard 6 and to a pin 28 on the frame side 1 to 15 yieldingly retain the standard in its rearward position against the stop 29.

In order to effect variation in the length of the impulses and spacing between impulses, the stop 29 and relatively fixed contact point are adjustable. Adjustment of 20 the stop is effected by forming it as a screw and threading it into an ear 31 that projects inwardly from the frame side 1, the rear end of the screw being provided with a knurled 25 button 32 whereby it may be manipulated. A jam-nut 33 is provided on the stop for engagement with the face of the ear 31 to hold the screw in adjusted position.

Referring now to the operating parts:

30 34 designates contact actuators rotatably mounted on the shaft 5, each having a feeler finger 35 over-lying the tape 3 and adapted for projection into perforations in the tape. There may be as many of the actuators 34 35 as there are lines of perforations in the tape and each actuator operates independently of all of the others although there is certain similarity owing to the fact that any one actuator may operate the movable contact 40 to close a circuit. The actuators 34 are preferably struck from sheet metal and each is provided with a wing 36 which is bent back parallel with its body part and rotatably mounted on the shaft, the wing of one actuator bearing against the body of an adjacent actuator to effect proper spacing and stabilization. The end of each of the feeler fingers 35 over-lies a groove 4 in the shaft 2 and is rounded to drop easily through a perforation and be lifted therefrom, as the tape 50 advances, without injuring the tape, the grooves in the shaft permitting the fingers to drop entirely through the tape and insure proper and complete actuation of the contact 55 mechanism.

Rising from the body of each actuator 34 is an arm 37 which lies back of the universal bar 8 and is adapted for engagement therewith to shift the bar when the finger 35 60 drops through a perforation in the tape, the arm 37 being normally held back of and out of engagement with the universal bar by support of the fingers 35 on the imperforate body of the tape between the perforations. 65 The fingers being yieldingly held in contact

with the tape and urged to project through a perforation by individual springs 38 which are connected with ears 39 on the actuators 34 and with teeth 40 on a plate 41 that extends between and is mounted on the side 70 frame members 1-1'. Each of the actuators 34 is a duplicate of the other and provided with an individual spring 38 so that any actuator may be operated independently of the others; i. e., when a perforation in the 75 tape passes beneath one of the feeler fingers 35, the spring 38 for that finger will throw the latter through the perforation and move its arm 37 against the universal bar 8 to effect engagement of the contact points, the 80 remaining fingers, being supported by the imperforate portion of the tape, remaining stationary. The spring 38 for each of the feeler fingers 35 is stronger than the spring 27 that holds the standard 6 rearwardly, so 85 that when a perforation in the tape permits movement of a feeler finger 35, the universal bar 8 will be thrown forwardly under tension of the spring 38 and against the tension of the spring 27. During this movement, 90 under influence of one of the fingers, the remain fingers remaining stationary.

In the operation of the device, assuming it to be set for favorable conditions, a tape 95 characterized by perforations for the sending of a message is run over the roller 2 and the feeler fingers 35 successively drop into the perforations to effect the making and breaking of the circuit. For illustration, should a portion of the tape characterized 100 for the sending of the word "him" be passed over the roller, a feeler finger 35 will successively drop through the four short perforations in the tape corresponding to the four dots of the character "h" to make and break 105 the circuit by four short contacts representative of four dots of the character in the telegraphic code. An imperforate portion of the tape of a length corresponding to a space 110 interval then occurs to hold the circuit open for a space interval; a finger then drops successively into two more short apertures 115 representative of two dots for the letter "i" and, after another space interval, a finger drops successively into two long apertures representative of the two dashes corresponding to the letter "m."

As the dot and dash apertures in the tape are of respective uniform length, the fingers project into the apertures for uniform periods for dots and other uniform periods for dashes, and induce contacts of corresponding periods for dots and dashes, the non-contacting periods, corresponding to intervals between the dots and dashes in a character and 125 between characters, also being uniform.

The periods of contact between the points 12 and 13 are dependent on the space relation of the adjustable, relatively fixed contact point to the movable point.

If short intervals between impulses are desired, as for a short line and favorable weather conditions, the stop 29 is set back so that the standard 6 will be yieldingly retained in rearward position and the relatively fixed contact is set back close to the point 12 on the standard 6 (Fig. IV). With this adjustment, a very slight movement of the point 12 will bring it into contact with the point 13 to close a circuit, as the universal bar 8 is in close relation to the arms 37 when the standard is set back as described, an arm will engage the universal bar immediately upon entry of its feeler finger into a tape aperture and move the bar to effect contact of the point 12 with the point 13. With this arrangement, the actuators will have but slight movement, which must be sufficient, however, to permit the fingers to project to some extent into an aperture, in order to permit the actuating movement. When the finger is so projected, its spring 38 is restrained by the contact as distinguished from the normal restraint by engagement of the finger with an imperforate portion of the tape. The contact of the points, beginning immediately upon projection of the finger into a tape aperture, is maintained until the finger is lifted by again engaging the tape at the end of the aperture, so that the period of contact corresponds to full length of the aperture and the period of spacing to full length of the preceding imperforate portion separating apertures longitudinally.

Should there be a voltage drop on account of the length of the line or a leakage due to weather conditions, the current will have a tendency to lag or "tail-out" and as a result the impulses will not break as sharply as under more favorable conditions but on the contrary will over-lap or "pile up" so as to render the signals unintelligible.

The objections just enumerated may be overcome by sending the impulses over the line at a relatively slow speed. Commercially, however, such a practice is objectionable because time is an important factor in telegraphy and the company cannot afford to tie up the lines by slowly sent messages. I have provided means whereby not only will danger of overlapping or "piling up" of impulses be eliminated, but the means also contemplates a mechanism by the use of which the time required to transmit such messages will not be increased.

According to my invention the actual time required to send the given dot and dash code will not exceed that now generally consumed because I have provided means whereby the "space interval" may be increased while the period of time which the contacts may remain closed will be reduced to compensate for the increased time the spacing period consumes. In this manner a sufficiently long time may elapse for the line to

clear itself after each sending impulse so that each impulse will be sharply defined at the receiving end of the line.

In order to maintain the best operating conditions it is essential that each make and break in the circuit be sharply defined; therefore, if a high potential line is employed, there will be danger of arcing unless the contacts move an appreciable distance apart at each opening movement of the circuit maker and breaker. If, however, a low potential line is employed, the movable contact may have a shorter amplitude of movement because the danger of arcing is decreased.

In the foregoing it will be apparent that in order to maintain high speed sending it will be necessary to shorten the duration of time the contacts remain closed and lengthen the duration of time the circuit is broken. This can be accomplished by adjusting the contact screw 24.

When a line of high potential is used and it becomes necessary to increase the breaking distance of the contact points in order to prevent arcing when the circuit is broken, the necessary adjustment may be made through the medium of the screw 32 which may be moved to the left to bring the universal bar 8 closer to the arm 11 thereby increasing the oscillation of arm 11 and creating a wider air gap for each opening movement of the circuit maker and breaker.

As movement of the point 12 is dependent upon pivotal movement of the actuator under influence of its spring, it is apparent that for such greater travel of the movable point there is a correspondingly greater projection of a selective finger into a tape aperture before the contact occurs. Consequently, as the return of the finger and resultant breaking of the contact occurs at the end of the perforation, irrespective of delay in making the contact, the space interval is increased to the extent of the additional projection of the finger into the aperture.

It is apparent that any desired variation of space interval may be effected within the range of adjustment of the stop and relatively fixed point.

Having thus described my invention, what I claim as new therein, and desire to secure by Letters-Patent, is:

1. In combination with relatively fixed and movable contact members, a record member having alternating portions for the support and release of an actuator, a yieldingly urged actuator supported by the record member and operable on the movable contact member when released, and adjustable means restraining movement of the movable contact member.

2. Circuit making and breaking mechanism comprising a movable member having

a contact point, means for yieldingly retaining said member in set position, adjustable means co-operative with said member to vary its set position, a relatively fixed member, having a contact point, adjustable toward and from the movable member, and an actuator for the movable member.

3. Circuit making and breaking mechanism comprising relatively fixed and movable contact members, one adjustable and the other having an adjustable stop whereby space relation therebetween may be varied by variation in set position of both, and means for actuating the movable member to effect contact thereof with the relatively fixed member.

4. Circuit making and breaking mechanism comprising relatively fixed and movable contact members, an adjustable stop for the movable member, means yieldingly urging the movable member to set position against the stop, and a plurality of actuators having fixed set positions and each independently operable on the movable member.

5. Circuit making and breaking mechanism comprising a movable contact member, an adjustable, relatively fixed contact member, means yieldingly urging the movable member away from the fixed member, an adjustable stop for limiting such movement, actuating mechanism yieldingly urged to move the movable member to contact with the fixed member, and a record member co-

operative with the selective mechanism to 35 actuate said actuating mechanism.

6. Circuit making and breaking mechanism comprising relatively fixed and movable contact members, a stop for the movable member, a spring normally retaining 40 the movable member against the stop and in spaced relation to the relatively fixed member, a universal bar on the movable member, a plurality of individual actuators each comprising an arm for engaging the 45 universal bar and a feeler finger, a spring for each actuator of greater strength than the contact member spring to move said member to contact position when the actuator is released, and a record member capable of supporting, releasing and restoring the actuators.

7. In combination with relatively fixed and movable contact members, a universal bar on the movable member, a plurality of 55 actuators rotatably mounted on the shaft and each having a wing also rotatably mounted on the shaft and contacting an adjacent actuator, an arm for engaging the universal bar and a feeler finger, a spring 60 for each actuator urging the arm to engagement with the universal bar and the finger toward a record member, and a record member operable on the actuators to effect operation of the movable contact member.

In testimony whereof I affix my signature.

EDWIN H. PIERSEN.
